UNITED STATES PATENT OFFICE.

WILLIS J. PERKINS, OF GRAND RAPIDS, MICHIGAN.

SHAFT-GUARD.

1,139,441.

Specification of Letters Patent.

Patented May 11, 1915.

Application filed December 24, 1909, Serial No. 534,849. Renewed June 3, 1912. Serial No. 701,429.

To all whom it may concern:

Be it known that I, WILLIS J. PERKINS, a citizen of the United States, residing at Grand Rapids, Michigan, have invented certain new and useful Improvements in Shaft-Guards, of which the following is a specification.

This invention relates to improvements in shaft guards.

10 The main objects of this invention are: First, to provide an improved shaft guard which is economical and efficient and protects the shaft in whole or in part throughout its length, and certain parts carried thereby or attached thereto. Second, to provide an improved shaft guard which can be quickly and easily applied to a shaft without removing the shaft from its supports or bearings, and is readily adapted 20 to any length or diameter of shaft.

Further objects, and objects relating to structural details, will definitely appear from the detailed description to follow.

I accomplish the objects of my invention 25 by the devices and means described in the following specification. The structure described constitutes one effective embodiment of my invention. Other embodiments could be readily devised by those skilled in the 30 art.

The invention is clearly defined and pointed out in the claims.

A structure constituting an effective and preferred embodiment of the features of my 35 invention is clearly illustrated in the accompanying drawing, forming a part of this specification, in which:—

Figure 1 is a detail elevation of a structure embodying the features of my invention, parts being broken away to better show details. Fig. 2 is a horizontal section, taken on a line corresponding to line 4—4 of Fig. 1, showing a supporting collar between sections of the spiral guard. Fig. 3 is 45 a vertical section, through one of the guard collars, taken on a line corresponding to line 7—7 of Fig. 1. Fig. 4 is a detail view, showing the method of applying the cushioning layer to the shaft. Fig. 5 is a detail 50 view of my improved guard, shown without collar supports.

In the drawings, similar reference characters refer to similar parts throughout the several views, and the sectional views are 55 taken looking in the direction of the little arrows at the ends of the section lines.

Referring to the drawing, 1 represents a shaft having my improved guard thereon, sections of the shaft being illustrated. Pulleys 2 and 2 are shown upon the shaft, each 60 pulley being secured by means of a key 3 arranged in a key-seat 4, as is common practice.

My improved shaft guard preferably consists of a spiral coil 5 of steel ribbon, which 65 is arranged upon the shaft loosely so that the shaft is free to revolve independently thereof. The end turns of the coil 5 may be embraced and supported by collars 6, illustrated in the drawing. These collars are 70 loosely mounted upon the shaft so that the shaft revolves independently thereof. The end of the coil may be riveted and the collar omitted as described hereinafter.

For convenience in assembling, the collars 6 are split longitudinally and provided with circumferential flanges 8, between which are ears 9 adapted to receive the screw 10 so that the collars can be readily placed upon the shaft when the shaft is in position. A flange 7 is on the collar and embraces and holds the end of the spiral guard. On the end of the collar next to the pulley hub or collar, I provide a flange 7', which 75 loosely embraces the same. When the collar is placed between pulley hubs close together, flanges 7' are on both ends. Where the shaft is of such length as to require a plurality of the guard coils, 5, I preferably provide collars 6 at intermediate points with 80 a flange 7 on each side to embrace the ends of adjacent coils, as illustrated in Figs. 1 and 2. The guard may be put on in independent sections where the conditions render it advisable. Where it is desired to prevent noise, I provide the shaft with a 85 cushion covering 11 inside of the guard. This covering is preferably a strip or ribbon of fabric wound upon the shaft, spirally,—see Fig. 4,—and coated with asphalt or the like.

To apply the covering, I first preferably coat the shaft with asphalt or any suitable adhesive material and wind the fabric thereon, the fabric being in the form of a 105 spirally-wound strip, and then apply an outer coating of asphalt or suitable material. This secures the fabric to the shaft and forms an effective cushioning or silencing device for the guard. By applying an 110 outer coating of asphalt or suitable material, the edges of the strip are covered and

secured so that a practically continuous sheathing is provided for the shaft.

My improved guard can be readily applied to any shaft in its operative position by winding the strip forming the guard coil thereon and providing the split or longitudinally-divided collars, as described, or otherwise, protecting the terminals. The coils may be made of any length or number of sections to meet the particular requirements so that it is not necessary to make the same to any size or length, the only parts necessary to make the proper size being the collars, when collars are used.

15 My improved shaft guard may be applied to the end of a shaft by placing a collar 1' thereon, and providing a flange 7', which extends over the said collar, thereby protecting the same,—see Fig. 1. This is especially desirable, where the end of the shaft is unsupported. Any shaft, however, is usually supported at the end, as shown extending into a suitable box in a hanger 24, here shown conventionally.

20 25 After winding the guard strip upon the shaft, the collars when used are applied, as illustrated, a double flange collar being preferably used where it is necessary or desirable to use a plurality of the guard coils.

30 It is evident that the coils may be made any length desired, the length being regulated according to the particular requirements or conditions. Sections can be supported by double collars, as appears in Fig. 35 1. The supporting collars may be omitted and the spiral secured by riveting or securing its end. (See Fig. 5.) The riveted or secured end forms a collar 5' integral with the spiral guard and forms a complete bearing. 40 It is the full equivalent of the collar 6 and is properly regarded as a collar, and, as indicated above, is the preferred form when an extra supplemental collar is used.

Where pulleys are close together—see 45 Fig. 1—the collars 6 may be used without the spiral, with a flange 7' at each end.

50 My improved guard is very economical in cost of material and very economically applied. Further, it may be shipped or transported in a form which occupies a minimum space and is of convenient form to assemble. While a flat or ribbon wire or tape-like strip is preferred by me, a round wire is quite satisfactory. I am aware of the fact 55 that there are many flexible shaftings which are revolvable within a spiral casing. The casing itself is fixed in the relation to the shaft and does not revolve with it. Such a structure is exemplified in United States 60 Letters Patent No. 486,852 of November 29, 1892, to G. H. Coates, for flexible shaft. I do not regard these properly as shaft guards or as comparable with my device which is

solely for the protection of the shaft and not to support and guide the same. In my 65 structure, the shaft, it will be noted, is illustrated as substantially longitudinally inflexible and therefore differs from these so-called flexible shafts.

I have illustrated and described my improved guard in detail in the form in which I have embodied it in practice, as I find that form to be efficient and satisfactory. I am, however, aware that it can be considerably varied in structural details, and I wish 75 to be understood as not only claiming the invention in the specific form illustrated, but also broadly, as appears in the appended claims.

Having thus described my invention, what 80 I claim as new and desire to secure by Letters Patent is:—

1. In a structure of the class described, the combination with the shaft, of sections of spiral coil arranged loosely thereon; collars having laterally-projecting annular flanges embracing the ends of said coil sections, the intermediate collars being provided with a pair of the laterally-projecting annular flanges embracing the adjacent ends 90 of the coil sections, all said parts loosely embracing and freely revolvable on said shaft; and a cushion layer on said shaft within said coil.

2. In a structure of the class described, 95 the combination with the shaft, of sections of spiral coil arranged loosely thereon; collars having laterally-projecting annular flanges embracing the ends of said coil sections, the intermediate collars being provided with a pair of the laterally-projecting annular flanges embracing the adjacent ends 100 of the coil sections, all said parts loosely embracing and freely revolvable on said shaft.

3. In a structure of the class described, the combination with a substantially straight rigid shaft and bearings therefor, of an independently revolvable guard, comprising a spiral coil closed into complete circles forming bearings for said guard at the ends thereof said guard being loosely and revolvably mounted on said shaft, whereby the shaft is freely revolvable within said guard and said guard is adapted to normally revolve with said shaft and is free to revolve on said shaft and relative to said shaft and said bearings when functioning as a guard.

In witness whereof, I have hereunto set my hand and seal in the presence of two 120 witnesses.

WILLIS J. PERKINS. [L. S.]
